STOKER

George von Haase, Lakewood, Ohio, assignor to
The American Ship Building Company, Cleve-
land, Ohio, a corporation of New Jersey

Application April 22, 1931, Serial No. 532,002

3 Claims. (Cl. 110—32)

This invention relates to mechanical stokers, and more particularly to a device of this kind of improved and simplified form.

An object of this invention is to provide a mechanical stoker having a movable grate comprising interchangeable grate bars, and in which the arrangement of structure is such as to permit broken or burned grate bars to be readily replaced.

10 Another object of this invention is to provide a mechanical stoker having grate actuating, and fuel feeding means so arranged as to permit the use of a hand-firing door.

15 Another object of this invention is to provide a mechanical stoker embodying novel grate actuating means.

Still another object of this invention is to provide a stoker in which the fuel supplying means embodies novel means for distributing the fuel 20 substantially uniformly upon the receiving end of the grate.

A further object of this invention is to provide a mechanical stoker in which novel means is employed for selectively regulating the speed of the 25 fuel feeding means and of the grate actuating means.

The invention may be further briefly summarized as consisting in certain novel combinations and arrangements of parts hereinafter described and particularly set out in the appended 30 claims.

In the accompanying sheets of drawings,

Fig. 1 is a side elevational view, with parts thereof in section, showing a boiler furnace having the stoker mechanism of my invention associated therewith;

Fig. 2 is a longitudinal sectional elevation taken through one of the boiler furnaces and its stoker mechanism;

40 Fig. 3 is a front elevation of one of the furnace fronts;

Fig. 4 is a sectional plan view taken substantially on the line 4—4 of Fig. 3;

Fig. 5 is a partial elevational view showing the 45 means for regulating the speed of the grate actuating means and of the fuel feeding means;

Fig. 6 is a plan view showing the fuel distributing member;

Fig. 7 is an end elevational view thereof;

50 Fig. 8 is an elevational view showing one pair of the grate bar supporting bridges;

Fig. 9 is a plan view thereof;

Fig. 10 is a detail elevational view of the grate operating cam;

55 Fig. 11 is an end elevation thereof; and

Fig. 12 is a partial sectional elevation showing another form of grate bar support.

In the drawings, to which detailed reference will presently be made, I have shown the mechanical stoker of my invention as being associated with a marine type Scotch boiler, but before proceeding with this detailed description, it will be understood, of course, that my invention may be embodied in various structural forms other than the particular one herein illustrated, 10 and that my stoker may be used with other boilers than the particular type mentioned.

In the preferred form of my invention, as illustrated in the drawings, I have shown my stoker mechanism applied to a fire tube boiler 15. The 15 boiler is shown as being provided with a conventional tubular furnace 17 which is equipped with a furnace front 18. The furnace front is provided with a hand firing door 19, and in addition to the usual function of the furnace front, 20 namely that of forming a closure for the outer end of the furnace, it also constitutes a support for the fuel feeding means and for the grate actuating means of my stoker mechanism which are to be more fully described hereinafter. 25

As is usual in boilers of this type, the furnaces 17 are of a cylindrical, corrugated form, as shown in Figs. 1 and 2, and extend into the boiler shell between the front head 20 thereof and the forward wall 21 of the secondary combustion 30 chamber. It will be understood, of course, that each furnace is equipped with my stoker mechanism, but to simplify the description, detailed reference will be made to but one of the furnace units. A plurality of grate bars 22 extend longitudinally within the furnace in adjacent parallel relation to form a grate upon which the fuel is burned. These bars are supported within the furnace at such a height as to provide an air space 23 beneath the grate. The grate bars are 40 all of the same form so as to be interchangeable, thus facilitating the replacement of bars which are burned or broken. At their forward end, or, in other words, at the end of the bars nearest the furnace front, I provide the block-like end portions 24 which fit relatively close together, so as to leave but a restricted air passage between the same and to form a fuel receiving table or platen extending transversely of the grate.

To support the grate bars 22 so that the same 50 may be moved longitudinally within the furnace to thereby progressively advance the fuel being burned, I provide pairs of transversely extending movable supporting bars or bridge members adjacent the ends of the grate. At the forward 55

or fuel receiving end of the grate, this supporting means comprises the bridge members 25 and 26, and the supporting means at the rear or discharge end of the grate comprises the bridge members 27 and 28. As shown in Figs. 8 and 9, these bridge members extend transversely of the furnace, and at their ends are provided with wedge-shaped bearing lugs or portions 29 engaging in V-shaped bearing recesses formed in the supporting members 30, which latter members are secured to the wall of the furnace. Along their longitudinal top edges, the bridge members are provided with spaced lugs 31 of rounded form constituting bearing projections which engage in similarly shaped bearing recesses 32 formed in the grate bars adjacent the ends thereof. This engagement of the bearing projections in the recesses of the grate bars affords a connection between these parts whereby tilting of the bridge members upon their supports 30 from the position illustrated in Fig. 2 to the position illustrated in Fig. 1, produces the desired longitudinal movement of the grate bars.

As stated above, the grate bars are identical in form, and it should be noted, at this point, that two adjacent bearing recesses 32 are provided at both ends of each bar. Likewise, it should be noted that the bearing projections 31 of each pair of bridge members are in staggered relation, as shown in Figs. 8 and 9. This arrangement of bearing projections and bearing recesses permits alternate grate bars to be supported upon the bridge members 26 and 28, while intermediate grate bars are supported upon bridge members 25 and 27. It will be seen from this arrangement that the grate bars constitute two sets which are movable relative to each other. In other words, the grate constitutes two sets of bars, one of which is supported upon the bridge members 26 and 28 and the other of which is supported upon the bridge members 25 and 27, so that inclination of either of these sets of bridge members will cause longitudinal movement of one set of grate bars relative to the other set.

Adjacent its inner end, the furnace 17 is provided with a transversely extending rear wall 33 of suitable construction. This wall is spaced from the discharge end of the movable grate so as to form an ash pit 34 into which the ash and clinkers drop from the discharge end of the grate. The ash pit is separated from the air space 23 beneath the grate by means of a transversely extending plate member 35 and a damper 36 pivoted adjacent the plate member. The position of this damper may be adjusted from the front of the boiler by means of the rod 37 to thereby vary the amount of air which is allowed to pass from the air space into the ash pit, or to permit the removal of ashes from the pit. It will be noted that the plate member 35 is so formed and arranged as to leave a transversely extending air passage 38 between this member and the grate. This air passage constitutes a by-pass for the damper whereby air may be admitted to the ash pit from the air space 23 during such time that the damper is closed. The admission of air to the ash pit through the passage insures a proper supply of secondary air for mixture with the heated volatile gases distilled from the coal, at a point, and in such volume, as to result in efficient combustion of these gases.

As already stated, the pairs of bridge members afford a support for the grate whereby the sets of grate bars can be moved longitudinally within the furnace to advance the fuel being burned.

In the stoker mechanism herein disclosed, I provide actuating means presently to be described in detail, whereby the sets of grate bars are moved simultaneously in the fuel advancing direction, or, in other words, away from the furnace front, and are retracted or moved toward the furnace front in succession independently of each other. During their fuel advancing movement, both sets of grate bars are moved at the same time, and consequently they advance the fuel bed as a whole. After the sets of bars have completed their fuel advancing movement, one set of bars is retracted beneath the fuel bed while the other set remains stationary. After the retracting movement of the first set of grate bars has been completed, this set remains stationary while the second set of bars is retracted under the fuel bed. Upon completion of the retracting movement of the second set of bars, both sets of bars are then ready for another cycle of operation beginning with the fuel advancing movement just described.

For actuating the grate bars to carry out the cycle of operation just described, I provide a cross-head guiding member 40 which is supported upon the furnace front 18 just below the hand-firing door 19, and in which is reciprocably mounted a plurality of cross-heads 41 and 42. The cross-heads 41 are two in number, and are connected with the bridge member 26 by means of pairs of links 43, so that upon reciprocating movement of these cross-heads the bridge members 26 and 28 will be given a tilting movement and the set of grate bars supported thereby will be moved longitudinally. The cross-head 42, which is arranged intermediate the pair of cross-heads 41, is provided with a connecting rod 44 which extends through an opening provided in the bridge member 26 and has a loose connection with the bridge member 25. This loose connection, as herein shown, constitutes a rounded bearing member 45 mounted upon the end of the rod for engagement in a similarly shaped bearing recess provided in the bridge member 25. As clearly shown in Fig. 2 of the drawings, this loose connection serves to actuate the set of grate bars carried by the bridge members 25 and 27 in their retracting direction, but does not impart motion to this set of grate bars in the opposite or fuel advancing direction. It will be seen from this arrangement that when the cross-heads 41 are actuated in the direction to advance the set of grate bars carried by the bridge members 26 and 28, the latter members engage the bridge members 25 and 27 and cause the set of grate bars carried by the latter to be simultaneously advanced. Upon movement of the cross-heads 41 in the retracting direction, the bridge members 26 and 28 are tilted, and the grate bars carried thereby are retracted while the bridge members 25 and 27 remain stationary. Upon movement of the cross-head 42 in the retracting direction, the rod 44 tilts the bridge member 25, causing the set of grate bars carried thereby to be retracted.

To actuate the cross-heads in timed relation to produce the grate bar movement described, I provide a rotary cam member 46 which is keyed or otherwise secured to an actuating shaft 47. The cross-heads 41 and 42 are preferably of the same form of construction, which, as clearly shown in Fig. 2, is substantially U-shaped. The cross-heads are supported within the cross-head guide 40 with the spaced legs 48 and 49 forming bearing portions, and with those legs straddling

the actuating cam 46. The legs 48 and 49 are provided, respectively, with integral lug portions 50 and 51 which are formed with inclined contact surfaces adapted to be engaged by radially projecting cam portions 52 and 53 provided on the member 46. The cam portions 52 are two in number to correspond with the number of cross-heads 41, and are arranged in alignment with each other axially of the member 46. The cam portion 53, which cooperates with the contact surfaces of the cross-head 42, is located on the member 46 at a point intermediate the cam portions 52 and is also spaced from the latter circumferentially of the member 46 approximately 60°, so that as the member is rotated the cam portion 53 will always lag behind the cam portions 52.

As viewed in Fig. 2 of the drawings, the rotation of the cam member 46 is in a clockwise direction, and with the parts in the relative positions shown in this figure, the cam portions 52 have just engaged the contact lugs 50 of the cross-heads 41. Further rotary movement of the member 46 causes the cross-heads 41 to be moved toward the boiler, and, as explained above, all of the grate bars are thereby moved simultaneously in the fuel advancing direction until the cam portions 52 disengage the contact lugs 50. Continued rotary movement of the member 46 causes the cam portions 52 to engage the contact lugs 51 of the cross-heads 41 to retract the set of grate bars carried by the bridge members 26 and 28. This retracting movement continues until the member 46 is rotated sufficiently to cause the cam portions 52 to disengage the contact lugs 51. Thereafter, the cam portion 53 engages the contact lug 51 of the cross-head 42, causing this cross-head, and the rod 44 connected thereto, to be moved in a direction to retract the set of grate bars carried by the bridge members 25 and 27.

In Fig. 12 of the drawings, I have shown another form of support for the discharge end of the sets of grate bars which may be used to advantage instead of the rocking bridge members 27 and 28. This support comprises a stationary bridge bar 27' extending transversely of the furnace adjacent the discharge end of the grate. The bridge bar is appropriately shaped to have the requisite strength to support the discharge ends of both sets of movable grate bars. As clearly shown in this figure, the top portion of the bridge bar forms a platen or table 28' having a top surface which is dished or concave. The width of this table 28', or in other words its dimension in the direction of the longitudinal axis of the furnace is preferably somewhat greater than the extent of the longitudinal movement of the grate bars so that the grate bar portions which engage the concave table surface will not overtravel the edges of the latter.

When the bridge bar 27' is employed, all of the grate bars are provided, adjacent their discharge ends, with one or more rounded bearing lugs or projections which frictionally engage, and ride in the concavity of the table 28' as the grate bars are reciprocated. The provision of concave bearing means for the discharge end of the sets of grate bars, causes the bars of one set to have a dipping movement in the vertical plane relative to the other set of bars, and this dipping of the sets of bars as they are reciprocated greatly facilitates the advancement of the fuel being burned.

For supplying fuel to the furnace, I provide fuel feeding mechanism which is supported on the furnace front at a point above and in the

clear of the hand-firing door 19 so as not to interfere with the latter during hand-firing operations. This fuel feeding means includes a hollow fitting 55 having a passage 56 leading through the furnace front and communicating with the interior of the furnace. The fitting 55 is provided with a hopper 57 of suitable shape, which is arranged to feed fuel into the passage 56. The fuel may be advanced within the passage 56 toward the furnace, as by means of a plunger 58 which is reciprocably mounted in the fitting 55 and actuated by the crank 59 of the drive shaft 60 through the connecting rod 61.

In order to properly distribute the fuel supplied through the passage 56, so that the same will be delivered substantially uniformly across the receiving end of the grate, I provide a distributing member 62 which is of peculiar shape, and which is arranged to cooperate with the inner end of the fuel supply passage 56. This distributing member is formed with a substantially horizontally disposed table portion 63 which, as shown in Figs. 2, 6, and 7, is slightly dished, or, in other words, has a semi-circular edge or lip 64 elevated somewhat above the bottom portion 65 which is substantially flush with the bottom wall of the passage 56. This raised semi-circular edge 64 forms a sloping weir-like barrier which affords some resistance to the fuel being delivered upon the table portion from the passage 56. As the fuel is pushed upon the table portion 63 by the action of the plunger 58, it travels up the sloping barrier and over the semi-circular edge 64 dropping down upon the receiving end of the grate. In order to obtain proper distribution of the fuel as it drops from the table portion, I provide the distributing member with a depending portion 66 which is flared or inclined downwardly and outwardly relative to the table portion. This depending portion of the distributing member, as shown in Figs. 6 and 7, is part of the surface of a cone. This inclined flaring surface represents that part of a cone which would remain after the other parts of the cone had been sheared away by a vertical plane passing substantially through the edge 67, and a horizontal plane passing through the line 68 representing the top edge of the semi-circular lip of the table 63. The frusto-conical portion 66 of the distributing member causes the fuel, which is pushed over the edge 64 of the table, to be distributed substantially uniformly across the receiving end of the grate, because as the particles of fuel are pushed over the edge of the table, they fall by gravity along lines representing elements of the frusto-conical surface and are thereby caused to diverge or fan out to produce the desired distribution. The fuel descends along the frusto-conical surface 66, as just explained, and continues to travel along lines representing elements of that surface until the particles reach the sheared edge 67 from which they drop downwardly in a vertical direction upon the receiving end of the grate.

It should be noted that the inverted U-shape formation, given to the depending frusto-conical portion 66, straddles the opening for the hand-firing door 19, and thus affords clearance for hand-firing operations so that the distributing member need not be removed to perform these operations or to replace broken grate bars.

If desired, a transversely extending plate 69 may be provided to prevent fuel from dropping off the receiving end of the grate. This transversely extending plate also serves as an abutment for preventing the fuel from moving toward the fur-

nace front with the grate bars as the latter are being retracted.

For actuating the fuel feeding means and the grate mechanism, I provide a bell crank fitting 74 which is arranged adjacent the furnace front and is adapted to be oscillated as by means of a vertical link 75 adapted to be reciprocated by any suitable driving means. The fitting 74 is supported in suitable bearings 76 carried by the furnace front, and actuates the fuel feeding means and the grate mechanism through the links 77 and 78. This fitting is formed with a crank arm 79 to which the upper end of the link 75 is pivoted and is also provided with angularly disposed lever arms 80 and 81 which are operably connected, respectively, with one end each of the links 77 and 78. The opposite end of the link 77 is pivoted to an arm 82 which is journaled upon the crankshaft 60. A ratchet pawl 83 is associated with the arm 82 for engagement with a ratchet wheel 84 which is keyed to the shaft 60. By this arrangement, it will be seen that oscillation of the fitting 74 will cause oscillation of the lever 82 which, in turn, drives the crankshaft 60 through the ratchet mechanism to cause reciprocation of the fuel feeding plunger 58. The link 78 is similarly connected through a ratchet mechanism 85 to a pinion 86 which meshes with a gear 87. This latter gear is keyed to the shaft 47 upon which the cross-head actuating cam 46 is mounted.

For selectively varying the speed of operation of the fuel feeding means and of the grate actuating means, I provide the lever arms 80 and 81 with adjustable pivotal connections for the links 77 and 78. These adjustable connections are of similar construction, each comprising a block 88 which is slideable in a slot 89 provided in the lever arm. The block 88 has pivotal connection with its link and is adapted to be actuated in its slot by means of a screw 90 extending through the block. The screw 90 is preferably provided with a readily accessible squared portion 91 at the end thereof, so that by the application of a suitable tool the block can be conveniently adjusted to provide the desired effective lever arm length to drive the feeding mechanism or grate mechanism at the desired speed. It will be noted, of course, that the means for adjusting the speed of the fuel feeding mechanism is entirely independent of the means for adjusting the grate actuating mechanism, so that the speed of operation of these mechanisms can be selectively regulated as desired to produce the most efficient operation of the stoker mechanism.

It will now be readily understood that I have provided an improved and simplified form of stoker mechanism which embodies novel means for distributing the fuel to the fuel receiving end

of the movable grate substantially uniformly under all conditions of operation, and which also embodies novel grate actuating means. It will also be readily seen that I have provided simple and efficient means for controlling the speed of operation of the fuel feeding means, and of the grate actuating mechanism, so that these functions can be regulated independently of each other for most efficient operation. Moreover, it will be seen that the arrangement of my stoker mechanism is such as to permit broken grate bars to be readily replaced, and such that hand-firing may be resorted to if desirable or necessary.

Having thus described my invention, I claim:

1. In a stoker, the combination of a furnace having a hand-firing door and a longitudinally movable grate, means for delivering fuel to said furnace at a point located above and in the clear of said door, means disposed below and in the clear of said door for actuating said grate, and deflecting means adapted to receive fuel from said delivering means and to distribute the same substantially uniformly upon the receiving end of said grate, said deflecting means comprising a member having a table portion formed with an upwardly sloping wall and having an arcuate edge and a frusto-conical deflecting portion depending from said arcuate edge, the latter portion of said deflecting means being of substantially inverted U-shape and arranged to straddle the opening for said door.

2. In fuel feeding apparatus, the combination with a combustion chamber having a door-controlled opening, of a fuel supply conduit disposed above said opening and communicating with said combustion chamber, and distributing means associated with the delivery end of said conduit, said distributing means comprising a member having a table portion formed with an upwardly sloping wall and having an arcuate edge, and a frusto-conical deflecting portion depending from said arcuate edge, said frusto-conical portion having an opening through the wall substantially in line with the door-controlled opening.

3. In fuel feeding apparatus, the combination of a fuel supply conduit, distributing means associated with the delivery end of said conduit, said distributing means comprising a member having an approximately horizontally disposed concave fuel-receiving table provided with an elevated arcuate edge and a substantially frusto-conical deflecting portion formed integral with said table and depending from said arcuate edge, and fuel advancing means operable in said conduit for gradually pushing the fuel across said table and over said elevated arcuate edge whereby the fuel descends by gravity along said deflecting portion.

GEORGE VON HAASE.
